UNITED STATES PATENT OFFICE.

JAMES LAKE, JR., OF BROOKLYN, NEW YORK, ASSIGNOR TO JAMES LAKE'S SONS, OF NEW YORK, N. Y., A CORPORATION OF NEW YORK.

HAT-MACHINE PRESS.

Application filed January 6, 1919. Serial No. 269,876.

To all whom it may concern:

Be it known that I, JAMES LAKE, Jr., a citizen of the United States, and a resident of the city of New York, borough of Brooklyn, in the county of Kings and State of New York, have invented a new and Improved Hat-Machine Press, of which the following is a full, clear, and exact description.

Among the principal objects which the present invention has in view are: to provide means for preventing a press of the character mentioned from opening accidentally; to provide manually-controlled means for opening and closing said press rapidly; to provide means for varying the extent of opening for the operating table of the machine; to provide means for adjusting the working positions of various portions of the press; and to simplify the construction and to strengthen the same.

It is a primary object to provide means for adjusting the distance between a movable heating table with related hat-brim die, and a stationary press-head cylinder mounted on the frame of the machine.

Drawings.

Figure 1 is a front elevation of a press constructed and arranged in accordance with the present invention;

Figure 2 is a vertical section, the section being taken as on the line 2—2 in Figure 1;

Figure 3 is a side elevation, a portion of the frame being cut away partly in section to show the transverse construction of the lower frame members of the press;

Figure 4 is a horizontal section, showing on an enlarged scale, a fragment of the machine press, the section being taken as on the line 4—4 in Figure 2;

Figure 5 is a fragmentary section taken as on the line 5—5 in Figure 2;

Figure 6 is a detail view in perspective, of fragments of the toggle locking frame for elevating and lowering the working table of the press;

Figure 7 is a plan section on an enlarged scale, showing a fragment of the guide supporting frame and an adjacent fragment of the operating table;

Figure 8 is a vertical section on an en-

larged scale, showing interior fragments of the operating table, movable parts connected therewith, and heating system therefor.

55

Description.

As seen in the drawings, the herein-described press has a stationary press-head cylinder 15. The cylinder 15 is permanently attached by brackets 16 to a stationary cross head 17. The cylinder 15 of the present disclosure is interiorly equipped in substantially the same manner and with similar elements as those shown in a patent granted to me under date of July 18, 1916, and num-

bered 1,191,709, to which patent cross reference is here made. Whereas, however, the press-head cylinder in the former patent is reciprocated together with the cross head by

which it is supported, in the present machine both the cylinder 15 and the cross head 17 are stationary. The cross head 17 is supported by framing legs 18, the feet 19 whereof form the supporting foundation for the machine. The legs 18 at the lower ends thereof, are structurally connected or tied by a tie rod 20, which prevents the said legs from spreading. Each of the legs has a vertical passage 21 formed therein for guid-

ing the runner blocks 22 formed at the lateral extremities of the heating table 23, and the reinforcing fins 24 thereof. The table 23 has a centrally disposed cylindrical chamber for holding a crown shape above a tippet member movably mounted therein and is

adapted for supporting a removable brim die 25, the contour whereof corresponds to the shape to be imparted to the brim of the hat when pressure is applied by a flexible face forming the interior of the cylinder 15,

as more fully set forth in the patent above referred to.

The weight of the table 23 and parts attached thereto is partially counterbalanced by the block 26. The block 26 is operatively connected with the runner blocks 22 by cables 27, which are roved over pulley segments 28 and 29, and are connected to the blocks 22 by pivot heads 30 and pins 31. The opposite ends of the cables 27 are attached to the eyelets 32 in eye-bars 33. The eye-bars 33 are provided as guides for sup-

80

100

plemental weight 34, which may be added to the block 26 to augment the effective weight thereof.

The table 23 and parts supported thereby are elevated and depressed by a mechanism manually controlled through a lever bar 35, the hand grip 36 whereof is grasped by the attendant of the machine when desired, to move the lever from the position shown in Figure 3 to that disclosed in Figure 2, the result of which is to move the table 23 into closed relation with the cylinder 15.

The mechanism for elevating the table 23 above referred to, consists primarily of toggle frames, the links 37 and 38 whereof are pivotally connected by pins 39. The pins 39 also serve to connect the strap links 40 with the links 37 and 38. The strap links 40 are connected by pivot pins 41, with rocking arms 42, which are mounted on the square shaft 43. The square shaft 43 is pivotally mounted in bearings in brackets 44 extended from the bolting plates 45. The brackets 44 are integral with the plates 45, and have feet 46, which rest against the web of one of the I-beams framing the adjustable cross head 47. On the lateral extremities of the cross-head 47 is integrally formed a runner block 47^a slidably confined 30 in each guideway to hold the crosshead in vertical alignment with the machine. The cross head 47 is complementary to the cross head 17, and is structurally connected with and suspended from said cross head 17 by the four suspension rods 48. The rods 48 are held in parallel alinement by the bolting plates 45 and 49, and extend through recesses in the exposed flanges of the I-beams forming the cross head. The extremities of the rods 48 are threaded and provided with nuts 50. The nuts 50 are adjusted to extend or contract the distance between the cross heads 17 and 47. This distance, it will be understood, corresponds with the height of the die 25 and the consequent working level of the table 23 in relation to the cylinder 15.

As seen best in Figure 6 of the drawings, the link 37 has a rearwardly-extended toe 51, a rearwardly-extended heel 52 being formed on the edge of the links 38. The abutting surfaces of the toe and heel mentioned are dressed or machined to rest firmly upon each other when the toggle frames formed by the links 37 and 38 are in locked 55 position or in the position where the planes of the two frames are angularly disposed, the connecting pivots thereof having passed the plane coincident with the hinge pivots thereof. In this position, the toes 51 and heels 52 prevent the frames from further forward movement when pressure is applied to the table 23, while the angular disposition of the two frames prevents a rearward movement of the joint of the said 60 frames. It is obvious that the predomi-

nance in length of the lever 35 over the arms 42, facilities the forceful closure of the toggle frames whereby any miscalculation in the adjustment of the cross-heads 17 and 47 may be accommodated without requiring readjustment thereof.

It will be understood that the table 23 and the die 25 carried thereby are lifted by the toggle frames and seated against the flexible inner wall of the cylinder 15 force- 75 fully.

In the manufacture of hats for which the present machine is particularly designed, the rough shapes are steamed. Before elevating the table 23 and die 25 thereon, one 80 of the rough shapes at each operation, is adjusted to said die. When the die is closed, the upper surface thereof presses upon and forces the brim of the hat against the inner lining of the cylinder 15. The 85 crown bag 53 with which machines of this character are usually provided is encompassed by a crown mold 54, a section whereof is shown in Figure 8 of the drawings, which rests on the tip plate 55. The tip 90 plate 55 and the table 23 are steam-heated. The tip plate has a steam space 56 provided therein, which is connected by means of the pipe 57, with a steam space 58 in the table 23. As best shown in Figure 8, 95 the pipe 57 is telescopically mounted in a tube 59, which is connected by a short pipe nipple 60 with said steam space 58.

As shown in Figure 2 of the drawings, steam is delivered to the space 58 in the 100 table 23 by a supply pipe 61. After circulating through the space 58, nipple 60, tube 59, pipe 57, and steam space 56, the steam passes from said steam space 56 by way of the pipe 62 and tube 63 to a waste pipe 105 64. A telescopic connection is provided between the tube 63 and the pipe 62. A supply of steam is provided for the table and the crown tip in this manner, the heat whereof is transmitted to the die 25 and 110 mold 54.

As shown best in Figure 8 of the drawings, the telescopic connection between the pipe 57 and the tube 59, and the pipe 62 and the tube 63, is required by the necessity for raising and lowering the mold 54, to adjust the press for the manufacture of hats having crowns of various sizes and shapes. To do this, the tip 55 is raised and lowered.

In the present machine, to raise and lower the tip 55, a screw-threaded nut 65 is provided. The nut 65 is thread engaged with an elevating screw 66, as shown best in Figure 8 of the drawings. The upper end of 125 the screw 66 is connected with a tubular extension 67 of the tip 55, by means of a pin 68. The nut 65 has an annular flange 69, supported by a cover plate 70 at the bottom of the tubular extension 71 of the 130

table 23. The cover plate 70 is centrally provided with a circular opening, through which a raised crown head of the nut 65 extends. The head has permanently mounted thereon a ratchet 72, the teeth whereof are engaged by the tooth end of a spring-seated pawl 73. To seat the pawl 73, a spiral spring 74 is provided as shown in said Figure 8. The tooth 75 of the pawl 73 is beveled at one side to engage the teeth of the ratchet on the flat side thereof, a form of pawl-and-ratchet well known to the art.

Provision is made by the use of the ratchet and pawl for reversing the operation of the pawl on the ratchet, which is accomplished by retracting the pawl 73 and rotating it on the axis to present the squared face thereof in relatively opposite rotary directions of the ratchet 72. The pawl 73 is mounted in the hub of a lever 76, the hand grip 77 of which, as shown best in Figure 3, is within easy reach of the attendant of the machine. By operating the lever 76, the attendant can readily increase or decrease the proportionate amount of pressure of the machine on the crown without affecting the pressure which is exerted upon the brim of the hat being pressed.

The pressure relied upon for pressing hats is hydraulic, water under pressure being admitted to the crown bag 53, by way of the pipe 78, tube 79, pipe 80, and tube 81, which has a screw-threaded extension 82. The tube 80 opens within the crown bag 53 and a rigid top plate thereof to deliver water to the said bag for pressing the crown independently of the rim. A screw nut having a hand wheel 83 is operated in the bowed bridge 84 to raise and lower the tube 81 and the crown bag supported thereby. To show the pressure on the water employed in the hydraulic operation, a pressure gage 85 is employed.

Water under pressure is supplied by the pipe 86, shown best in Figure 1 of the drawings, an extension 87 thereof entering the cylinder 15 within the space covered by the flexible lining of the said cylinder, which lining corresponds with the upper shape of the die 25. A valve 88 controls the flow of water through the pipe 86.

In the operation of the machine, the attendant having adjusted the operating position of the cross head 47 to the working position of the table 23 and parts supported thereby, places on the die 25 a rough shape and first gripping the hand rest 23^a, he grasps the hand grip 36 of the lever 35, and moves the same from the position shown in Figure 3, to that shown in Figure 2, with the result that the toggle frames having the links 37 and 38 are straightened and thrown past the center of a plane coincident with the pivots of the said

frames until the toes 51 of the links engage and rest upon the heels 52 of the said links. In this position, the rough hat shape is given a relatively slight preliminary pressure by the inner lining of the cylinder 70 15, and by the outer surface of the bag 53. In this position, the valve 89 having been turned off, the valve 88 is opened and water from the pipe 86 is permitted to flow through the pipes 78 and 87, respectively, 75 to the bag 53, and the cylinder 15, imparting to the said bag and cylinder the full pressure of the water supply. When the hat shape has received the desired pressure, the attendant closes the valve 88 and opens 80 the valve 89, thereby permitting sufficient of the water held in the cylinder 15 and bag 53 to escape to relieve the pressure on the said bag and cylinder, the water going to waste through the pipe 90.

If for any reason, it is desired to maintain pressure on the crown of the hat after the pressure is relieved from the brim thereof, the valve 91 is closed before the valve 89 is opened. When, therefore, the valve 90 89 is opened, it is obvious that pressure will be relieved from the cylinder 15 without relieving pressure from the bag 53.

The pressure surface of the bag 53 and of the brim die 25 being great, the resultant strain on the machinery is correspondingly great. Machines of this character have been subject to breakage for this reason. It is to overcome this objection that the links 37 and 38 and the brackets 16 have been disposed in line and intermediate the center of the machine and the rods 48 connecting the cross heads 17 and 47. By this arrangement, the lines of resistance to the strain are balanced to equalize the strain and to avoid 100 torsional stresses on the mechanism.

It is obvious that the rapidity with which the machine may be operated is augmented, when by the operation of the single lever 35, the clamping elements of the machine are 110 closed and locked in operative position.

Claims.

1. A press as characterized comprising a plurality of standing side frames disposed in spaced relation each of said frames having vertical guides on the inner faces thereof; a rigid cross head fixedly mounted on said standing frames adjacent the upper ends thereof; a movable cross head extending between said frames and engaging the guide members thereof; a plurality of suspension rods operatively connecting said fixed and movable cross heads, and screw nuts engaging said rods for raising or lowering the 115 same to establish the working distance between said cross heads; a liquid press fixedly mounted and dependent from the first mentioned cross head; a movable mold carrying 120 table, said table engaging the standing 125
- 65
- 130

frames in guided relation; elevating means for said table embodying a plurality of toggle levers, said levers being pivotally connected and operatively engaging said second 5 mentioned cross head and said table, the points of engagement for said levers with said table and said second mentioned cross head being at opposite sides of the center of said cross head and table for distributing the 10 strain applied by said pressure member; manual means for placing the said toggle levers in rigid locked position between said cross head and table, said means embodying a rocking shaft supported on said second 15 mentioned cross head and laterally disposed thereto; a hand lever for rocking said shaft; articulated means operatively connecting said rocking shaft and the pivotal joint of said toggle levers to place said toggle 20 levers in locked straight line position between said table and cross head supporting same; and a plurality of bracket members integrally formed on said toggle levers adjacent the pivotal connection thereof for ar- 25 resting the movement of said toggle levers at a point where said pivotal connection has slightly passed the vertical plane incorporating the pivotal connections of said levers with said table and cross head supporting the 30 same to automatically lock the toggle joints to prevent the collapsing thereof by the pressure applied on said table by said press.

2. A press as characterized comprising a plurality of standing side frames disposed in 35 spaced relation each of said frames having vertical guides on the inner faces thereof; a rigid cross head fixedly mounted on said standing frames adjacent the upper ends thereof; a movable cross head extending be- 40 tween said frames and engaging the guide members thereof; a plurality of suspension rods operatively connecting said fixed and movable cross heads, and screw nuts engaging said rods for raising or lowering the 45 same to establish the working distance be- 50 tween said cross heads; a liquid press fixedly mounted and dependent from the first mentioned cross head; a movable mold carrying table, said table engaging the standing frames in guided relation; elevating means for said table embodying a plurality of toggle levers, said levers being pivotally connected and operatively engaging said second 55 mentioned cross head and said table, the points of engagement for said levers with said table and said second mentioned cross head being at opposite sides of the center of said cross head and table for distributing the strain applied by said pressure member; 60 and manual means for placing the said toggle levers in rigid locked position between said cross head and table, said means embodying a rocking shaft supported on said second mentioned cross head and laterally disposed thereto; a hand lever for rocking 65

said shaft; articulated means operatively connecting said rocking shaft and the pivotal joint of said toggle levers to place said toggle levers in locked straight line position between said table and cross head supporting same; and a plurality of bracket members integrally formed on said toggle levers adjacent the pivotal connection thereof for arresting the movement of said toggle levers at a point where said pivotal connection has slightly passed the vertical plane incorporating the pivotal connections of said levers with said table and cross head supporting the same to automatically lock the toggle joints to prevent the collapsing thereof by the pressure applied on said table by said press; and a counterbalance engaging said table for assisting in elevating the same and parts connected therewith.

3. A press of the character disclosed comprising spaced frame members having alined guide slots, a relatively stationary cross-head supported by said frame members, a relatively movable cross-head having runners sliding in the guide slots, means adjustably connecting said cross-heads in spaced relation, cooperating press members, one carried by one of the cross-heads and the other having runners sliding in the guide slots, toggle mechanism interposed between said last-mentioned member of the press and the other cross-head, toggle actuating means operably connected with the toggle mechanism and having a pivotal support mounted with its axis laterally offset to one side of the plane of the guide slots, cooperating stops to limit relative motion of said elements and automatic counterbalancing means for the movable press member and toggle mechanism.

4. In a press of the character disclosed, side frames provided with alined guide-ways, an I-beam structure supported between said side frames, a movable press member engaging the guide-ways, toggle levers pivotally connected between the I-beam structure and said movable press member, substantially in the plane of the guide-ways, brackets supported on the I-beam structure, said brackets extending laterally to one side of the guide-ways and having feet bearing on the web of the I-beam structure to thereby brace said brackets in their laterally offset position, an operating member connected with the toggle levers and journaled in the offset portions of said brackets with its pivotal axis laterally offset from the I-beam structure and cooperating stops positioned to positively limit the straightening motion of the toggle.

5. A press as characterized comprising a plurality of standing side frames disposed in spaced relation each of said frames having vertical guides on the inner faces thereof, a rigid cross-head fixedly mounted on said

standing frames adjacent the upper ends thereof, a movable cross-head extending between said frames and engaging the guide members thereof, a plurality of suspension rods operatively connecting said fixed and movable cross-heads and screw nuts engaging said rods for raising or lowering the same to establish the working distance between said cross-heads, a movable mold carrying table, said table engaging the standing frames in guided relation, elevating means for said table embodying a plurality of toggle levers, said levers being pivotally connected and operatively engaging said second mentioned cross-head and said table, the points of engagement for said levers with said table and said second mentioned cross-head being at opposite sides of the center of said cross-head and table for distributing the strain applied by said pressure member, manual means for placing the said toggle levers in rigid locked position between

25
30
35
40
45

said cross-head and table, said means embodying a rocking shaft supported on said second mentioned cross-head and laterally disposed thereto, a hand lever for rocking said shaft, articulated means operatively connecting said rocking shaft and the pivotal joint of said toggle levers to place said toggle levers in locked straight line position between said table and cross-head supporting same and a plurality of bracket members integrally formed on said toggle levers adjacent the pivotal connection thereof for arresting the movement of said toggle levers at a point where said pivotal connection has slightly passed the vertical plane incorporating the pivotal connections of said levers with said table and cross-head supporting the same to automatically lock the toggle joints to prevent the collapsing thereof by the pressure applied on said table.

JAMES LAKE, JR.
